Specification for Design.

Patented Mar. 28, 1916.

Application filed December 28, 1915. Serial No. 69,120. Term of patent 14 years.

To all whom it may concern:

Be it known that I, ROLLIE B. FAGEOL, a citizen of the United States, residing in Oakland, county of Alameda, State of California, have invented a new, original, and ornamental Design for a Vehicle-Body, of which the following is a specification, reference being had to the accompanying drawing, forming part thereof, wherein—

The figures are respectively a view in top plan and a view in side elevation of a vehicle body showing my new design.

I claim:—

The ornamental design for a vehicle body, as shown.

In witness whereof I have signed my name to this specification in the presence of two witnesses.

ROLLIE B. FAGEOL.
